ENGINE WORK STAND AND METHOD OF USING THE SAME

Henry M. Ross, Alexandria, Va.

Application September 4, 1953, Serial No. 378,529

18 Claims. (Cl. 214—152)

This invention is a method of and apparatus for transferring an engine, particularly a jet engine, from its supports within an airplane to a movable engine work stand, and performing desired repair service and maintenance operations on said engine, and then replacing the engine in the plane. The invention contemplates the provision of means whereby the engine while on the stand may be supported in a manner to permit "run-up" tests when desired.

At the present time, considerable difficulty is experienced in servicing and repairing jet engines used to power airplanes, and no satisfactory jet engine handling equipment is available so far as is known. The known equipment of this kind all includes the use of flexible rigging or cables either supported from an overhead hoist, such as in common use aboard ships, or conventional wheeled cranes with appropriate winch as used in hangars ashore. Neither of these rigs is satisfactory because of the heavy weight of the jet engines to be handled and the tendency of such engines to sway when supported from above on flexible hoist rigging. With these difficulties in mind, the present invention has for an object the provision of a method and means by which a jet engine while supported within a plane body may be operatively engaged by a pair of rigid arms or finger pins and lifted from the engine supports on the plane without the use of block and tackle or flexible cable rigging of any kind.

Another object of the invention is to provide on a wheeled dolly, an engine work stand of the character described which is designed to supportingly engage the engine and which includes means operable when the dolly is moved clear of the plane to raise and lower the engine as well as to tilt the engine about either a transverse axis or about a longitudinal axis.

Another object of the invention is to provide means for mounting the engine for repairs, service, and maintenance operations on finger pins which are engaged in the hollow supporting trunnions provided on jet engines, together with means by which the engine may be transferred from said finger pins to bearing members designed and positioned to receive and support said trunnions when it is desired to perform a "run-up" test or similar tests involving actual operation of the engine while on the stand. At these times the finger pins are removed from the trunnions.

The invention also includes various adjuncts to enable one readily to position the engine as to height or angular position about either the horizontal or longitudinal axis, and to stabilize the engine and its mount in any of said positions.

In some forms of jet-powered planes, the openings into the hollow bores of the engine-carried trunnions are partially obstructed by parts of the plane body when the rear section of the body is removed to expose the engine. The invention provides means for handling these engines by providing longitudinally sectionalized finger pins which are magnetized so that the several complementary

2

parts of the pins are self-adhering but are separable with respect to each other, so that the pin section may be inserted into the trunnion bores sequentially and thus insure the trunnion bores be substantially completely filled by the sectionalized pins assembled therein, whereby to equalize the stresses within the trunnions incident to the support and manipulation of the engine on said pins.

These and other objects of the invention will become apparent from the following specification read in connection with the accompanying drawings, wherein there is illustrated a preferred form of the invention. In the drawings,

Fig. 1 is a perspective view of the engine stand of the present invention;

Fig. 2 is a side elevation of the invention showing in dotted lines the outline of an engine supported on the stand;

Fig. 3 is an end elevation of the stand;

Fig. 4 is a disassembled perspective view of one sectionalized finger pin;

Fig. 5 is a diagrammatic view illustrating the hydraulic system for raising, lowering, and tilting the engine stand; and

Fig. 6 is a fragmental detail of an engine-carried trunnion supported in a conventional pillow block.

In the drawings, wherein like reference numerals are used to designate like parts throughout, the invention is shown as comprising a base 1 composed of structural members 2 and 3, said structural members being united to form a generally rectangular frame in which the members 2 may conveniently be designated as end pieces and the members 3 as side pieces. The base 1 is shown as a skeleton frame without deck or flooring, but if desired a deck or flooring may be employed.

The base 1 furnishes support for spaced, opposed, upright members 4 shown supported upon the side pieces 3. Each of the uprights 4 comprises generally upwardly inclined structural members 5, 5 secured together at their upper ends in any convenient manner such as by welding. The upright members 4 are mounted in spaced, opposed relation at opposite sides of the base 1, and each of the upright members includes a vertically adjustable member 6 having a lower, stationary portion 7 and an upper, relatively movable section 8. The sections 7 and 8 are, as shown, telescopically engaged, and as will be herein-after described, the overall length of the members 6 may be hydraulically controlled.

The upper terminal portions of the sections 8 include arcuate supporting portions 9, said portions 9 having their axes disposed generally transversely of the base 1. Each arcuate member 9 is provided with trunnion members 10 which support for pivotal movement about an axis transverse to the axis of the arcuate members 9, a slide bearing 11. The slide bearings 11 are designed to provide support for an engine supporting yoke 12 in a manner to provide for pivotal movement of said yoke about a transverse, horizontal axis as well as pivotally about axes passing through the trunnions 10. The engine supporting yoke 12 is provided with terminal portions 13 which are fitted within the slide bearing members 11 and are designed to have sliding and rotary movement with respect to said bearings. The yoke member 12, as shown more particularly in Fig. 3, is thus suspended from the bearing members 11 in a manner to depend between the opposed, spaced, upright members 4 and is pivotally movable about an axis passing through said bearings 11. There is provided a hydraulic cylinder 14 mounted upon each section 8 for pivotal movement between a pair of spaced brackets 15 secured to the respective sections 8, 8. Each of the cylinders 14 is provided with a piston 16 connected to the yoke member 12 through bracket arms 17 secured thereto. The

manner in which the hydraulic cylinders 14 are controlled will be more clearly described hereinafter.

The yoke member 12 is designed to support an engine to be serviced or tested, and to this end is provided with a pair of supporting brackets 13 which project from the plane of the yoke member in a direction opposite to the bracket arms 17, 17. The brackets 13 in turn support adjustable slide plates 19 slotted as at 20, and engaged within the slots are bolt members 21; this arrangement permitting the plates 19 to be adjusted towards and away from the plane of the yoke member 12 for adjustment purposes, as will be more particularly referred to hereinafter. The plates 19 are each provided with an upset free terminal portion 22 on which is mounted a finger pin carrying member 23, as is more clearly apparent from Fig. 4. The finger pin carrying members 23 are each provided with a longitudinal groove 24 within which the upset terminal portion 22 of the plates 19 are received, and in order to provide for the transverse adjustment of the pin carrying member 23 with respect to the plates 19, the said plates are slotted as at 25 and a bolt 26 passes slidably through the slot and into threaded engagement with a threaded hole 27 disposed within the groove 24. By this arrangement, pin carrying members 23 may be adjusted towards and away from each other to vary the distance therebetween, to facilitate engagement and disengagement of the finger pins with respect to the bores of the hollow engine carried trunnions, as will later be described. Each of the pin carrying members 23 is provided with sectionalized finger pins 28 (see Fig. 4). Each of the pins 28 is, as shown, divided longitudinally on a plane passing through its axis to provide at least one separable pin section 29 which is complementary to a pin section 30 rigid with the pin carrying member 23. The pin sections 29 and 30 when assembled form a substantially cylindrical finger pin which may be inserted within the hollow bore of an engine carried trunnion as will later appear. For convenience in manipulating the pin sections 29 and 30, they are preferably magnetized so as to render the complementary sections self-adhering and at the same time permit ready separation for sequential insertion of the pin sections within the bores of the engine carried trunnions, as will later be described.

The upright members 4 are each provided with means to support a laterally adjustable plate 31. As shown, the upright members carry upwardly projecting bolts 32 which pass through a slot 33 in the plate 31, the slots 33 and bolts 32 being positioned so that the plates 31 may be shifted laterally towards and away from each other to vary the spacing therebetween. Each of the plates 31 carries a pillow block or bearing 34, the two bearings being aligned horizontally to define an axis of support for an engine when the latter is to be subjected to a "run-up" test or similar tests involving actual operation of the engine. The pillow blocks or bearings 34 may include a stationary bottom bearing section 35 and an upper movable bearing section 36 pivotally connected thereto together with a securing yoke member 37 pivoted to the lower bearing section 35 so that it may be swung into overlapping relation with the movable bearing section 36 when the latter is in trunnion enclosing position to secure the bearing sections together in a known manner. The pillow blocks 34 are positioned adjustably but rigidly on the upright members 4 and as shown in Fig. 3, are disposed vertically beneath the respective finger pins 28 for a purpose to be hereinafter more fully described.

In order to stabilize the yoke member 12 when desired, there is provided a turn buckle strut 38 pivotally connected at one end to a pair of spaced ears or lugs 39 carried by the inside face 40 of the adjacent end member 2, and at its opposite end to a pair of spaced lugs or brackets, not shown, carried by the yoke 12. Thus, when desired, the strut 38 may be adjusted to a proper

length, and connected as described between the end member 2 and the yoke 12 to stabilize the yoke against turning, in an angular position of adjustment in which it may have been placed.

5 An adjustable rear supporting column for an engine mounted on the stand is provided at 41, said column being pivotally connected at its lower end to the same end member 2 by spaced lugs 42 and carrying at its upper end a yoke shaped support 43 having engine engaging rollers 44 at the upper terminal portions of the yoke arms. Preferably, the rear engine supporting column 41 is adjustable, and to this end is made in the form of a conventional hydraulic jack, fluid under pressure being provided therefor by a hand operated pump 45 operatively connected to the lower portion of the column 41 by a properly valved conduit 46.

A further stabilizing strut 47 is provided, and the same is pivotally connected to the yoke member 12 substantially at its center. This strut is of the turn buckle type similar in all respects to that shown at 38 and is designed and arranged to be connected to the engine when the latter is mounted on the pins 28, for the purpose of stabilizing the engine within the yoke. In this respect, it might be noted that the engine is normally provided with a pair of ears 48 to which a stabilizing element is attached when the engine is mounted in a plane, and these same ears 48 are employed to receive the upper end of the strut 47 when the engine is removed from the plane and is supported on the pins 28 as previously described.

30 As previously stated, I prefer to provide hydraulic means for raising and lowering the sections 8, 8 of the upright members 4 and for pivotally moving the yoke member 12 angularly within its supporting bearings 11, and to this end the sections 7, 7 of the upright member 4 are in the form of hydraulic cylinders and receive piston members, not shown, carried by the lower ends of the sections 8, 8. Manually operable pump means 49 are provided for supplying hydraulic fluid under pressure for the hydraulic cylinders 7, 7 and the hydraulic cylinders 14, 14. Any convenient fluid reservoir such as 50 may be provided on the base 1, and the pump 49 may draw fluid therefrom through a line 51 and discharge the same under pressure through a conduit 52. The conduit 52 may deliver fluid under pressure to a control valve 53 from whence said fluid may be selectively delivered to the cylinders 7, 7 through lines 54 and to the cylinders 14, 14 through lines 55. The operating fluid delivered to the cylinders 14 may conveniently pass through the trunnions by which the cylinders are pivotally supported from the brackets 15. The valve 53 is arranged selectively to deliver fluid either in unison or individually to the cylinders 7, 7 in order to raise and lower the yoke, or to tilt the yoke about a longitudinal axis of the engine, by moving one of the sections 8, 8 to a higher elevation than the other, for a purpose to be hereinafter described. The valve 53 controls jointly flow of fluid to the cylinders 14, 14. The discharge of fluid from the cylinders 14, 14 and from the cylinders 7, 7 may be controlled by suitable exhaust valves 56 and for convenience, the valves 53 and 56 may be mounted upon a control board 57 which in turn is mounted upon one of the upright members 4. In Fig. 5, I have shown diagrammatically one form of hydraulic system which may be conveniently employed for selectively energizing the cylinders 7 and 14, and as shown, each of the lines beyond the master control valve 53 includes a check valve 58.

70 For convenience in moving the engine stand of the present invention from place to place, it is desirable to provide casters therefor, and to this end, casters 59 are provided. The casters 59 are shown mounted on swinging links 60 which in turn are pivotally connected to arms 61 carried by feet 62, the latter being rigidly secured to the base 1 in any desired manner. The arrangement

just described is for the purpose of selectively placing the casters into or out of operative relation with respect to the frame 1 by swinging the links 60 about their pivots 63. It will be understood that when the arms 64 carried by the links 60 are moved to their lower position as shown in Fig. 1, the casters are moved into operative position and the base 1 may then be readily moved from place to place, whereas when the arms 64 are moved to an elevated position, not shown, the casters are swung out of operative position with the result that the rigid feet 62 engage the surface on which the base is supported and in effect, anchor the base against movement.

The stand of the present invention is designed particularly for removing jet engines from airplanes. Jet engines of the type to be handled by the present apparatus are provided with laterally projecting hollow trunnions 65 or bosses which, as shown in Fig. 6 are supported in pillow blocks carried by the plane structure 66. The pillow blocks generally includes a stationary base member 67 which may be secured by welding or any other suitable means to the plane structure 66. The base member 67 is provided with a segmental bearing surface 68, and a complementary bearing section 69 is provided, the latter being pivotally carried by the movable section of the pillow block 70. The sections 67 and 70 are secured in closed relation about the trunnion 65 by means of a pivoted locking bolt 71 in a well known manner. In some instances, the opening 72 to the hollow bore of the trunnion 65 is at least partially obstructed by an overhanging part of the plane structure as shown at 73. The present invention is designed particularly for interiorly engaging the hollow trunnions 65 by a pair of finger pins while the trunnions are still housed within the pillow blocks and removing the engine from the plane supported on said finger pins which are entered within said hollow trunnions. The manner in which the invention is employed is as follows:

Fig. 2 shows in dotted lines the section of a plane, the rear portion of which has been removed to expose the rear portion of the jet engine which is to be removed from the plane for service. The base 1, with the casters operatively engaging the floor surface, is rolled to a position beneath the plane, with the yoke 12 disposed in a substantially vertical plane and straddling the engine from beneath and with the pin carrying members 23 projecting forwardly of the upright members as shown in Fig. 2. The vertically adjustable sections 8 of the upright members 4 are then adjusted hydraulically to an elevation such that the axis through the bearings 11, 11 is substantially coincident with the center of gravity of the engine. A pair of pin carriers 23 is then selected, having finger pins 28 dimensioned to correspond to the hollow bores of the trunnions 65. It should be noted that there is some variations in the size of these bores between planes of different model, and it is therefore desirable to have on hand, several pin carriers 23 of sizes corresponding to the sizes encountered in servicing planes of different type so that a pin carrier having a pin of proper dimension may be mounted on the slide plates 19. It should also be noted that in planes of different type, there is a variation in the distance between the center of gravity of the engine and the location of the hollow supporting trunnions carried by the engines. This makes it desirable to have a selection of slide plates 19 of different dimensions corresponding to the requirements of the different engines. Having selected a pair of slide plates 19 of proper dimension for the engine to be serviced, these plates are mounted on the brackets 18 in a position of adjustment such that the pins 28 carried by the pin carriers 23 are in substantially horizontal alignment with the trunnions 65. As previously mentioned, the bores 72 of the trunnions 65 are sometimes obstructed by an overhanging part of the plane, and with this in mind, the section 29 of the sectionalized pin 28 is detached from the body of the pin and inserted through the unob-

structed portion of the trunnion opening 72. This section of the pin is then moved angularly within the bore of the trunnion until it occupies that portion of the bore which is obstructed by the overhanging part of the plane body. 5 It will be recalled that the pin sections are magnetized so that the inserted section of the pin will, by its magnetism, cling to the inner wall of the trunnion bore and maintain its position of adjustment. This position is generally one in which the flat longitudinal face of the 10 section is in a substantially vertical plane. With the pin sections 28 positioned as described, the pin carrying members 23 are now adjusted laterally and inwardly of the plates 19 until the rigid pin sections 30 carried thereby are 15 fully received within the hollow bores of the trunnions. 15 The pin carrying members 23 are then secured in such position by the adjustment bolt 26.

In the event the plane carrying the engine to be serviced does not occupy a truly horizontal position with the result that the trunnions 65 on opposite sides of the engine 20 do not lie in the same horizontal plane, the pin 28 on the high side of the engine should be engaged with its trunnion first, as described above. Then the hydraulic cylinder 7 on the low side of the engine should be actuated to permit lowering of that side of the yoke member until 25 the pin carrier 23 on the low side of the engine is in alignment with the low trunnion of the engine. The pin 28 carried by the low pin carrier is then engaged with the low engine trunnion, as above described. This tilting of the engine yoke about the longitudinal axis of the 30 engine as just described is permissible due to the mounting of the yoke bearings 11 for pivotal movement about axes parallel to the axis of the engine, and the slide bearing provisions incorporated in the bearings 11.

With the finger pins 28 properly engaged within the 35 hollow bores of the trunnions 65 as above described, the hydraulic cylinders 7, 7 are energized to elevate the yoke slightly to take the weight of the engine off its plane supports. The rear engine supporting column 41 is then 40 brought into supporting relation with the tail section of the engine as shown in Fig. 2, after which the pillow blocks which enclose the engine carried trunnions are opened to release the trunnions. The lower engine mount which is employed within the plane for securing the engine to the mount rod is then released from the engine lugs 43 and the engine mounted on the finger pins is 45 then carefully moved clear of the plane by rolling the frame 1 aft. When the engine is clear of the plane, the stabilizing turn buckle strut 47 carried by the yoke 12 is attached at its upper end to the lower engine mount 50 including the lugs 43. With the engine thus supported on the stand, it may be raised or lowered by actuating the cylinders 7, 7, it may be turned about a horizontal axis passing through the bearings 11 by energizing the cylinders 14, or it may be tilted about a longitudinal axis 55 by differentially operating the cylinders 7, 7. It should be noted that after the turn buckle 47 is connected between the yoke 12 and the lower engine mount 43, the rear engine supporting column 41 may be lowered to an inoperative position.

As previously stated, the invention contemplates providing means for supporting the engine on the stand for "run-up" tests and similar tests requiring actual operation of the engine. The means for thus supporting the engine on the stand are the pillow block bearings 34. 60 Thus, when it is desired to perform a "run-up" or similar test on the engine, the cylinders 7, 7 are actuated until an appropriate index mark such as 74 carried by the members 8, 8 is in registration with the top of the hydraulic cylinders 7 or some other indicating portion of the 65 stationary structure, which will indicate that the engine is in a proper degree of elevation to be transferred to the pillow blocks 34. With the engine positioned at such correct height, the pillow blocks 34 are opened and the engine supporting yoke 12 tilted by appropriate action 70 of the cylinders 14 to move the yoke in a clockwise 75 of the cylinders 14 to move the yoke in a clockwise

direction as viewed in Fig. 1, and to an extent to bring the engine carried trunnions 65 within the open pillow blocks 34. The pillow blocks are then closed and secured and the finger pins 28 are withdrawn from the hollow trunnions. The engine is now supported by the trunnions exteriorly by the pillow blocks 34 within which they are enclosed. The engine may then be leveled by properly shifting the yoke angularly in a counterclockwise direction. It will be recalled that the yoke 12 is still attached to the engine by means of the stabilizing turn buckle 47, so that shifting of the yoke in the manner described will turn the engine about an axis through the pillow blocks 34. When the engine has been moved to a horizontal position, the yoke may be stabilized by attaching to it the free end of the turn buckle strut 38. The engine may now be operated in safety, since it is securely supported in the pillow blocks 34 and is stabilized with respect to the yoke by the turn buckle strut 47 and the yoke in turn is stabilized by the turn buckle strut 38. The engine may, when desired, be transferred to the finger pins 28 again by a reverse procedure and may be restored to the supporting pillow blocks in the plane by moving the base 1 with the engine supported thereon into operative relation with the open pillow blocks 67 of the engine and the finger pins then withdrawn and the stand removed.

At any time during the testing or servicing of the engine, the casters 59 may be moved out of engagement with the front or other supporting surface and the rigid feet 62 brought into supporting engagement with such surface.

From the foregoing it is apparent that I have provided a method of and apparatus for removing jet engines from airplanes, repairing and servicing them, and subjecting them to "run-up" tests without the use of any flexible support rigging, and in a manner such that the engine is at all times securely supported against undesirable movements such as are inherent in engine handling equipment characterized by the use of flexible rigging or cables for supporting the engine either during transport or operation.

I have illustrated in the accompanying drawings a desired form of my invention, but it is to be understood that minor changes can be made in the size and proportion of parts there shown without departing from the spirit of my invention, which is more clearly defined in the appended claims.

I claim:

1. An engine work stand comprising a base member, plural upright members mounted in opposed, spaced relation on said base member, an engine supporting member, means pivotally mounting the same at opposite ends on said upright members respectively, and a pair of engine engaging finger pins carried by the engine supporting member and adapted to engage within hollow open ended trunnions carried by the engine, the pins being disposed in spaced, opposed relation and aligned on an axis spaced from and generally parallel to the pivotal axis of said engine supporting member, and means for relatively adjusting the pins and said engine supporting member to vary the distance between said pins.

2. The apparatus described in claim 1 wherein an adjustable strut is mounted on said base and carries a yoke shaped engine engaging member and is adapted to be detachably connected to an engine supported on said engine supporting member, to stabilize the same.

3. The engine work stand described in claim 1 wherein at least one of said pins is contoured to provide a non-circular cross sectional area perpendicular to the axis thereof substantially corresponding to the cross sectional area of the accessible open end of the corresponding hollow engine trunnion.

4. The engine work stand described in claim 1 wherein at least one of said pins is substantially semi-cylindrical in form to permit the entrance thereof into a corresponding hollow engine trunnion even though the open end

thereof is partly obstructed, and a complemental, separable, magnetized, semi-cylindrical pin section magnetically adhered thereto.

5. The apparatus described in claim 1 wherein said pair of finger pins is mounted respectively on slide plates carried by the engine supporting member, said plates and engine supporting member being relatively adjustable to vary the distance between the pivotal axis of the engine supporting member and the axis defined by the finger pins.

10. 6. The apparatus described in claim 5 wherein the finger pins are adjustably mounted on said slide plates respectively, whereby to move the pins towards and from each other.

15. 7. The apparatus described in claim 1 wherein the pivotal mounting means for the engine supporting member includes a bearing member on each of said upright members and respectively supporting opposite ends of the engine supporting member and defining a generally horizontal pivotal axis therefor, and a trunnion pivotally mounting each said bearing member for movement about an axis transverse to the pivotal axis of said engine supporting member.

25. 8. The apparatus described in claim 7 wherein the upright members each include means for varying the height thereof and of the bearing members for the engine supporting member, and control means for selectively varying the height of said upright members jointly or individually, whereby the pivotal axis of the engine supporting member may be raised, lowered, or tilted as desired.

35. 9. The apparatus described in claim 7 wherein at least one of said bearings is a combined rotary and slide bearing to permit endwise movement of the engine supporting member therein, and wherein means are provided for tilting the pivotal axis of said engine supporting member about an axis generally transverse to said pivotal axis.

40. 10. The apparatus described in claim 1 wherein said engine supporting member is generally yoke-shaped and is mounted upon said upright members with the bridge portion of the yoke depending between said upright members to underlie an engine supported thereon.

45. 11. The apparatus described in claim 10 wherein an adjustable strut is provided on said base and is adapted to be detachably connected to said yoke to stabilize said yoke, when desired.

12. The apparatus described in claim 1 wherein means are provided for moving the engine supporting member angularly about said pivotal mounting.

50. 13. The apparatus described in claim 12 wherein a pair of spaced, open top bearing members are adjustably mounted on said base beneath said finger pins and adapted to be disposed respectively in generally vertical alignment with said finger pins and defining a generally horizontal axis whereby an engine supported by said pins on said engine supporting member may be moved to a position in which the engine trunnions are disposed within said open top bearing members by tilting the engine supporting means about its pivotal axis.

60. 14. The apparatus described in claim 13 wherein said open top bearing members are provided with bearing closure means, for retaining engine carried trunnions therein for "run up" tests.

65. 15. In a work stand for engines, means for supporting an engine provided with hollow trunnions projecting laterally therefrom, said means including a pair of spaced, axially-aligned finger pins adapted to fit within said hollow trunnions, means mounting the pins for axial movement toward and away from each other, at least one of said pins being sectioned longitudinally to provide a plurality of complemental pin sections, said sections being magnetized whereby the several pin sections are self-adhering, in a group, to form a complete pin but may be detached for successive insertion within one of said hollow trunnions.

16. In an engine work stand, an engine supporting member, spaced, aligned finger pins carried by the engine supporting member and defining a generally horizontal axis through the pins, each of said pins being sectionalized longitudinally to provide at least one pin section separable from the main body of the respective pins, said pins and sections thereof being magnetized to render them self-adhering.

17. The method of removing an engine from a plane within which it is supported on engine-carried, open-ended hollow trunnions and wherein the open ends of said trunnions are partially obstructed, comprising positioning an engine stand beneath the engine, aligning a pair of semi-cylindrical pins carried by said engine stand with the unobstructed portions of the open ends of the bores of the respective trunnions, inserting a magnetized semicylindrical pin section into each bore through the unobstructed portions thereof and moving said pin sections angularly about the axes of the respective bores into the obstructed portions thereof, inserting said first-mentioned semicylindrical pins within the unobstructed portions of said bores, releasing the supporting connections of the engine from the plane, and then moving the stand with the engine supported on said stand rearwardly away from the plane.

18. The method of removing an engine from a plane within which it is supported on engine carried hollow trunnions comprising positioning an engine stand beneath the engine, supporting a pair of axially aligned pins on the stand for rotation about an axis substantially parallel to

10

but spaced from the axis of said pin, aligning said pins with the bores of the respective trunnions, inserting said pins within said bores, releasing the supporting connections of the engine from the plane, moving the stand with the engine supported on said pins away from the plane, and rotating the engine about said axis of rotation to move said engine carried trunnions downwardly into supporting engagement with open top bearings provided therefor on said stand.
